UNITED STATES PATENT OFFICE

141,108

DESIGN FOR A DISPLAY STAND

Clinton J. Christopher, Minneapolis, Minn.

Application January 20, 1945, Serial No. 117,522

Term of patent 14 years

(Cl. D80—9)

To all whom it may concern:

Be it known that I, Clinton J. Christopher, a citizen of the United States, residing at Minneapolis, in the county of Hennepin and State of Minnesota, have invented a new, original, and ornamental Design for Display Stand, of which the following is a specification, reference being had to the accompanying drawing, in which the figure is a perspective view of a display stand showing my new design.

The ornamental design for a display stand, as shown.

CLINTON J. CHRISTOPHER.
